Patented Nov. 20, 1917.

BY
E. & J. F. Brandenburg,
ATTORNEYS

UNITED STATES PATENT OFFICE.

STUART ELLIS, OF WASHINGTON, DISTRICT OF COLUMBIA, ASSIGNOR, BY MESNE ASSIGNMENTS, TO METAL EGG CRATE COMPANY, A CORPORATION OF DELAWARE.

METALLIC SHIPPING-BOX.

1,247,517.

Specification of Letters Patent. Patented Nov. 20, 1917.

Application filed June 8, 1917. Serial No. 173,523.

To all whom it may concern:

Be it known that I, STUART ELLIS, a citizen of the United States, residing at Washington, in the District of Columbia, have 5 invented certain new and useful Improvements in Metallic Shipping-Boxes, of which the following is a specification.

The object, in general, of my invention is to provide a novel construction of metallic 10 shipping-box, specially adapted for use with the parcels post, and which will require no wrapping paper for transit through the mails. By eliminating the use of wrapping paper, a substantial financial saving is effected, especially since the cost of paper has 15 materially increased in recent years. Also, since no wrapping paper is necessary, the user is spared the loss of time and annoyance of wrapping up the box, preparatory to 20 mailing the same.

Another equally important object of the invention is to provide a metallic shipping box which may be repeatedly sent back and forth through the mails between the same 25 two persons (for instance, a truck-farmer living in the rural districts and a city customer of such farmer), without re-addressing the box each time it is re-mailed.

Another important object is to provide a 30 box carrying a reversible cardboard panel, to both faces of which postage-stamps may be affixed. Postage-stamps will not adhere satisfactorily to a metal surface, and, if applied directly to a metallic shipping box, 35 they quickly become detached. By the use of my reversible postage-stamp panel, postage-stamps to prepay the "going" trip through the mails may be gummed to one face thereof, and, for the "return" trip, the 40 stamps may be gummed to the reverse side, the panel being simply reversed when the box is mailed for its return trip.

Another object is to provide a metallic shipping box simple in construction and 45 cheap to manufacture, and one whose manner of use will be readily understood.

Subsidiary objects, relating to improvements in structural details, will appear as the specification proceeds and the nature of 50 the invention more fully unfolds.

With these objects in view, the invention contemplates the provision, in a metallic shipping-box of individually-reversible, address- and postage-stamp panels, disposed 55 within the box and discernible through the

lid thereof; and the invention resides, also, in certain other constructions, combinations and arrangements of parts, as will be hereinafter fully described in the specification, summed up in the claims, and illustrated in 60 the accompanying drawing.

The accompanying drawing graphically illustrates, as examples, certain forms of metallic shipping-boxes capable of carrying out the underlying principles of the invention. Like reference-characters denote corresponding parts throughout the several views. The different views may be briefly described as follows:

Fig. 1 is a fragmentary side elevation, 70 partly in section, of a metallic shipping-box constructed in accordance with my invention;

Fig. 2 is a detached, detail, collective view, 75 in perspective, of the address-panel and of the postage-stamp panel, showing the manner in which the latter is preferably carried by the former;

Fig. 3 is a plan view of the address- and 80 of the postage-stamp panels, showing the side thereof the reverse of that shown in Fig. 2;

Fig. 4 is a detached, detail view of the postage-stamp panel;

Fig. 5 is a top plan view of a slightly 85 modified form of metallic shipping-box, showing the hinged lid thereof closed; and

Fig. 6 is a view in section on the line 6—6 of Fig. 5, looking in the direction of the arrows, and showing the hinged lid raised. 90

Referring, now, in detail to the drawing and, first, to Figs. 1 to 4 thereof:

1 designates a metallic shipping-box provided with a lid 2 having apertures 3 and 4, through which the address- and postage-stamp panels, hereinafter particularly described, are visible. The box may be provided with a filler 5, comprising pasteboard strips arranged to form cells for holding eggs, or the like. On top of the filler 5 may 100 be placed a corrugated-cardboard plate 6, forming a top cushioning member. The filler 5 and the cushioning plate 6, however, form no part of my invention.

Adapted to be disposed beneath the lid 105 2,—for instance, upon the top of the cardboard plate 6,—is a reversible address-panel 7, appropriately of a size to contact with, or to nearly touch, the four walls of the box. This panel, from the standpoint 110

of cheapness, is, advantageously, constructed of cardboard, although, obviously it may be made of wood, or any other suitable material. This panel 7 is preferably provided with beveled corners 8, so as to permit a person's fingers easily to grasp the panel in removing it from the box, or placing it therein. The panel may have both faces thereof blocked off by rectilinear lines 9, 10 as shown in Figs. 2 and 3, and within these boundary lines may be suitably inscribed indicia 10 as to the identity of the sender and of the recipient of the box. Thus, by 15 glancing at Fig. 2, it will be seen that the name and address of the person to whom the box is to be delivered, as well as the name and address of the party sending the box, may be prominently displayed on that face of the panel shown in Fig. 2; and, on 20 the reverse side (as shown in Fig. 3), may, in like manner, be prominently displayed and properly arranged names and addresses enabling the person to whom the box has been delivered through the mails, as afore- 25 said, to re-mail the box to the person from whom he received it, as stated, by simply reversing the address-panel 7 in the box.

The invention also contemplates the provision of a second panel 11, constituting a 30 postage-stamp panel, and this latter panel may be conveniently carried by the address-panel 7 in a suitable manner. Thus, for example, the address-panel 7 may be provided with lateral slits 12, forming lateral tongues 35 13, 13, 13. By forcing the panel 11 in said slits (as shown in Fig. 2), so that its ends are beneath two of said tongues and its central portion over the third tongue, it is frictionally held in position. To enhance this 40 frictional hold, the panel 7 may be of sheet metal, having some resiliency, so that the tongues 13 spring against the panel 11.

To the panel 11 may be gummed postage-stamps 14. Thus, a person mailing the box 45 to another and wishing to prepay the return postage may place on the reverse side of the panel 11 stamps to pay for the return trip; so that all that the receiver of the box has to do, when he desires to return the box 50 to the original sender, is to reverse both the address and postage-stamp panels and re-mail the box. Thus, the same box may be repeatedly used between the same two persons, each person, when he receives the box 55 and desiring to return it to the other party, simply reversing both panels and properly positioning the postage-stamp panel 11 with respect to the address-panel 7.

Referring, now, to Figs. 5 and 6, disclosing 60 a slightly modified form of box embodying the same underlying principles: 2^a is the hinged lid of the box 1^a. The lid is provided with two pairs of slits 15, 15 and 15^a, 15^a, and the metal of the lid between each 65 two slits is depressed, forming, as it were,

countersunk supporting-beds or platforms 16. A reversible address-panel 17 is slipped through the slits or longitudinally-extending slots 15, 15 and over the bed or platform 16 (as shown in Figs. 5 and 6), and 70 is thus frictionally held in position. Desirably, the lid 2^a is of spring metal, enhancing the frictional hold on the panel. Similarly, a reversible postage-stamp panel 18 is slipped through the slots 15^a, 15^a and 75 over the bed 16. A latch 19 is provided, whereby the lid may be held in closed position.

Having thus fully described my invention, the many advantages thereof will be 80 apparent, especially to those skilled in the art to which it pertains. The box is exceedingly simple in construction, is cheap to manufacture, is of light weight, and its manner of use is easily understood by persons possessing even a limited intelligence. Other advantages may be noted as follows: 85 No wrapping paper is required; the metallic surface of the box is not defaced by stamps, and the postage-stamps are firmly gummed 90 to a surface other than the metallic surface of the box; after the names and addresses of the sender and receiver of the box have been once written or printed on the two surfaces of the address-panel, no subsequent 95 laborious and time-consuming addressing of the box is required, each time the box is re-mailed; and money and time are saved by the use of the box.

While, for the purposes of the patent 100 statutes, I have described with great particularity concrete embodiments of my invention, I am aware that various departures, especially in matters of structural detail, may be made; but it is to be understood that all variations as come within the spirit 105 of the appended claims, when read in connection with all mechanical equivalents for the different elements constituting the structure expressed in the claims, constitute no 110 departure from the scope of the invention.

Having thus fully described my invention, what I claim as new and desire to secure by Letters-Patent is:

1. In a parcels-post shipping-box, having 115 a lid, provided with apertures, a reversible address-panel within said box and discernible through one of said apertures when the lid is closed, and an independently-reversible postage-stamp panel removably carried 120 by said address-panel and discernible through one of said apertures when the lid is closed.

2. In a parcels post shipping-box, having 125 a lid, provided with apertures, a reversible address-panel within said box and discernible through one of said apertures when the lid is closed, and having tongues and an independently-reversible postage-stamp panel removably carried by said address-panel and 130

engaged by said tongues, and discernible through one of said apertures when the lid is closed.

3. In a parcels-post shipping-box, having a lid provided with apertures, a reversible address-panel within said box and discernible through one of said apertures when the lid is closed, said panel being slitted, form-

ing tongues, and an independently-reversible postage-stamp panel removably carried by said address-panel and engaged by said tongues, and discernible through one of said apertures when the lid is closed. 10

In testimony whereof, I affix my signature.

STUART ELLIS.
